INFANT'S BELT

Fleurette Crettaz Johnstone, Pasadena, Calif.

Application May 13, 1942, Serial No. 442,785

2 Claims. (Cl. 128—134)

This invention relates to an infant's belt for the purpose of restraining a baby in a chair or crib or the like.

An object of my invention is to provide a simple and easily attached infant's belt, which also includes means whereby the child's hands can be restrained, and the child is thus prevented from interfering with the food or the feeding process.

Another object of my invention is to provide a novel infant's belt of the character stated, which also includes ties by means of which the child can be restrained in a chair or a crib.

A feature of my invention resides in the construction of the belt, including the wrist cuffs which permit the child to move its hands somewhat, even though restrained, and also permit the child to hold a toy.

Other objects, advantages and features of invention may appear from the accompanying drawing, the subjoined detailed description and the appended claims.

In the drawing:

Figure 1 is a fragmentary side elevation of the outside of the belt.

Figure 2 is a side elevation of the inside of the belt.

Figure 3 is a perspective view of the belt.

Referring more particularly to the drawing, my belt includes an elongated strip 1, which may be made of cloth or other materials which are sufficiently soft to prevent injury to the child. A plurality of spaced eyelets 2 are provided at one end of the strip, and a plurality of eyelets 3 are provided at its other end.

A hook 4 is attached to one end of the belt and a hook 5 to the other end. The hook 4 engages the eyelets 3, and the hook 5 engages the eyelets 2, when the belt encircles the waist of a child, thus adjustably attaching the belt and also enabling the same to be attached quickly and easily. To prevent injury to the child from the hook 5, a lining strip 6 is stitched to the inside of the belt, and this lining strip extends over the eyelets 2, but not over the eyelets 3. Ties 7 and 8 are attached, one on each side of the belt, substantially as shown, for the purpose of attaching the belt to a chair, crib, or the like.

Reinforcing loops 9 and 10 are stitched to the belt and over the point of contact of the ties 7 and 8, respectively, for the purpose of reinforcing the point of attachment between the ties of

the belt. An open-ended cuff 11 and 12 is attached to the inner end of the ties 7 and 8, respectively. These cuffs are preferably stitched to the ties, although any suitable method of attachment may be employed. The ties 7 and 8 extend slightly beyond the loops 9 and 10, respectively, and the cuffs are attached to this extended portion of the ties, so that the child's hands will have a slight movement permitting the child to move its hands and play with a toy or the like.

A pair of laces 13 and 14 are stitched to the free ends of the cuffs 11 and 12, respectively, and these laces are tied around the wrist of the child, thus holding the cuff in position, and restraining the child's arms during feeding.

In actual use, I have found that the child is prevented from playing with the feeding dish, and its hands are sufficiently restrained for this purpose. However, some movement is permitted, so that the child will not fret.

Having described my invention, I claim:

1. An infant's belt comprising an elongated waist encircling band, the free end portions thereof being disposed in overlapping relation when the belt is worn, means for adjustably securing the overlapping ends of the band together, a pair of tie strips stitched adjacent their inner ends to the band at each side thereof, wrist encircling cuffs attached at their ends to the respective free inner ends of the tie strips, the outer ends of the cuffs being open, and tie strings forming closure means for the open outer ends of each cuff.

2. An infant's belt comprising an elongated waist encircling band, the free end portions thereof being disposed in overlapping relation when the belt is worn, each free end portion of the band being provided with a plurality of spaced eyelets, a hook on each end of the band engageable with the adjacent eyelet when the free ends of the band are disposed in overlapping relation for adjustably securing the overlapping ends of the band together, a pair of tie strips stitched adjacent their inner ends to the band at each side thereof, wrist encircling cuffs attached at their ends to the respective free inner ends of the tie strips, the outer ends of the cuffs being open, and tie strings forming closure means for the open outer ends of each cuff.

FLEURETTE CRETTAZ JOHNSTONE.
